Primary Examiner — Cynthia M. Chin*(74) Attorney, Agent, or Firm* — Harness Dickey & Pierce P.L.C.(57) **CLAIM**

The ornamental design for a personal transport vehicle, as shown and described.

DESCRIPTION

FIG. 1 is an isometric view of a personal transport vehicle in accordance with our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown are included for the purpose of illustrating portions of the personal transport vehicle which form no part of the claimed design.
